UNITED STATES PATENT OFFICE.

CARL H. HEMMING, OF NEW HAVEN, CONNECTICUT.

CUTLERY-POLISHING MACHINE.

1,422,358.

Specification of Letters Patent. Patented July 11, 1922.

Application filed January 10, 1920. Serial No. 350,556.

To all whom it may concern:

Be it known that I, CARL H. HEMMING, a citizen of the United States, residing at New Haven, in the county of New Haven and State of Connecticut, have invented certain new and useful Improvements in Cutlery-Polishing Machines; and I do hereby declare the following to be a full, clear, and exact description of the invention, such as will enable others skilled in the art to which it app pertains to make and use the same.

My invention relates to polishing machines of the type where the work is polished between opposed abrasion wheels.

Referring to the accompanying drawings wherein the same figures and letters of reference indicate like parts throughout the several views:

Fig. 1 represents a plan view of the machine;

Fig. 2 is a front elevation of the machine, broken view of the abrasion wheels, and supporting legs;

Fig. 3 is a side elevation of the machine looking in the direction of arrow *a*, Fig. 1, broken view of one of the driving pulleys and supporting legs with the abrasion wheels omitted;

Fig. 4 is an enlarged broken view partly in section relating to mechanism connected with the movement of one of the abrasion wheels; and

Fig. 5 is a detail view of a knife blade.

The opposed abrasion wheels 1 and 2 are mounted on their shafts 3—4 journaled in boxes 5—6 forming a part of the swinging standards 7—8. These standards are adjustably secured to the rock shafts 9—10, the latter shown more clearly in Fig. 3. These rock shafts are journaled in the standards 11—12 secured to the machine bed 13. The rock shafts are longitudinally adjusted to align the abrasion wheels through the medium of the short shafts 14—15 whose inner threaded ends 14^a—15^a register with and engage in threaded bores in the ends of said rock shafts, as indicated at 10^a in Figure 3, and 16—17 are standards in which the adjusting shafts 14—15 are rotatably located 50 and actuated by their hand wheels 18—19.

The periphery of the abrasion wheel 1 is normally located at the vertical central position or polishing center indicated by the dotted line *b*, Fig. 2, and is adjustably maintained in such central position by means of the adjusting screw 20 mounted in the stand-

ard 21. The inner end of this screw rests against the standard 7— and the opposite end carries the bevel pinion 22—see also Fig. 1—registering with the bevel pinion 23 carried by the shaft 24 journaled in the standards 25—26 and controlled by the hand wheel 27. 28 is a rod whose outer threaded end is mounted in the standard 29, and whose inner end is supported in an elongated opening—not shown—in the standard 7. This opening, however, is similar to the opening 30, Fig. 3, in the standard 8 and for the same purpose, viz: to enable the standards 7—8 to be longitudinally adjusted. 31—Fig. 2—is a tension spring located between the standard 7 and the adjustable hand-wheel 32 mounted on the threaded part of the rod 28. The opposite standard 8 is provided with similar mechanism, viz: the rod 33, adjustable hand-wheel 34, tension spring 35, and the supporting standard 36. As the springs 31—35 exert a constant tension against the standards 7—8 to bring the abrasion wheels in close relation during the polishing, they are designated as "wheel tension springs."

37 is a tube anchored at one end to the standard 38, with its opposite end projecting freely through the elongated opening 39—Fig. 3—of the swinging standard 8. Between the washer 40—see also Fig. 4—and the standard 38 is located the spring 41 adapted to be compressed by the chain 42 passing over the sprocket wheels 43—44, Fig. 2, and connecting with the foot treadle 45. The opposite end of this chain is secured—Fig. 4—to the movable pin 46 located in the open slot 47 formed in the outer end of the tube 37.

48 is an adjustable forked knife support having the small antifriction rollers 49 mounted in its upper ends and the additional supporting plate 50 projecting therefrom. 51 is a bar secured to this knife support having a sliding fit in the projection 52 secured to the bed. The lower end of this bar carries the roller 53 engaging the treadle 54, pivotally mounted in the bracket 55. The collars 56—57 are adjustably mounted on the bar 51, the former—Fig. 2—engaging the lower end of the projection 52 locates the extreme upper position of the knife support 48, and the latter 57 engaging the upper surface 52^a of the projection 52, locates the extreme lower position of the knife support.

The well known means for rotating the

polishing wheel shafts 3—4 on their swinging standards are briefly described as follows: 58—59 are tight pulleys mounted on the projecting ends of the polishing wheel shafts, and the projecting ends of the rock shafts 9—10 support three pulleys of the same size on each shaft. As all the pulleys on the rock shaft 9 are not shown, reference is had to Fig. 3, showing the pulleys 60—61 and 62 mounted on the rock shaft 10, or, in other words, secured to the sleeve 63 rotatably mounted on said shaft. Power is transmitted, from an outside source—not shown—to the pulley 62, and from thence to the pulley 59, on the polishing wheel shaft 4, through the medium of the belt 64. The pulleys 60—61, being secured together, form, practically, a single pulley. A similar arrangement, before mentioned, of pulleys are secured to the sleeve 65 mounted on the rock shaft, Fig. 1, two only of the pulleys, 66—67 being shown. The belt 68, Fig. 3, transmits the power to the fixed pulley 58 on the polishing wheel shaft 3.

25 As before mentioned, the face of the abrasion wheel 1 is normally located at the polishing center *b*, and as it wears away is maintained in such position by means of the adjusting screw 20. In operation, the large spring 41 is first compressed by the treadle 45 and chain 42 to bring the abrasion wheel 2 under the influence of the spring 35, whose stored up tension will force said wheel into its operative position shown in Fig. 2. As soon, therefore, as the large spring 41 is compressed, both wheels will then be placed under the influence of the wheel tension springs 31—35 during the polishing operation. This is an important feature, as the wheels are always in flexible contact with the work and are thus at liberty to come and go in accordance with any variation occurring in the thickness of the work. This flexible action of the wheels will also give a better finish to the work than can be obtained by maintaining an unyielding pressure of the wheels thereagainst.

Releasing the pressure on the foot treadle 45 will cause spring 41 to react and force the wheel 2 away from the wheel 1, with its standard 8 resting against the screw 69, which screw is adjustably mounted in the standard 70. This reaction of spring 41 will also restore tension in the spring 35.

55 As the contact point of the abrasion wheels, represented by the dotted line *c*, Fig. 2, is too narrow to cover comparatively large surfaces—like, for instance, butcher knives, carving knives, etc.—I have arranged the previously described adjustable knife support adapted to finish only one-half of wide blades as they are passed between the abrasion wheels. While one foot of the operator is continuously engaged with the treadle 45 during the polishing op-

eration, the other foot is at liberty to engage the other treadle 54 and elevate the knife support 48 into the position shown in Fig. 2, and when in such position, the lower half *d* of the blade 71, Fig. 5, will be finished. Releasing treadle 54, the knife holder will drop by gravity to a position for finishing the other half *e* of the blade. The collars 56—57 can be readily adjusted for blades of any width, while the floor 73 can serve as a stopping point for the treadle 45, and it can be adjusted with respect to such position by means of the turn-buckle 72.

Having thus described my invention, what I claim is:

1. A machine of the character described, comprising opposed abrasion wheels, rotatable shafts therefor journaled in standards mounted on rocker-shafts, and wheel tension springs adapted to normally force the wheels toward their central polishing position, means for normally holding one of said wheels in such central position, a spring of greater tension than the wheel tension springs adapted to force the other of said wheels into open position, and means adapted to temporarily release the greater tension spring and place said open positioned wheel under its wheel tension spring. 80

2. A machine of the character described 95 having opposed abrasion wheels, rotatable shafts therefor journaled in standards mounted on rocker shafts, and wheel tension springs adapted to normally force the wheels toward their central polishing position, means for normally and adjustably holding one of said wheels in such central position, a spring of greater tension than the wheel tension spring of the other wheel adapted to force said wheel into open position and thus compress its wheel tension spring, and foot treadle mechanism adapted to release the greater tension spring and place said open positioned wheel under the control of its wheel tension spring. 100

3. A polishing machine comprising opposed abrasion wheels, means adjustably supporting the same for movement toward and away from each other, means for supporting a piece of work between the wheels, 115 and means for axially adjusting the wheels independently of each other and relative to the work supporting means.

4. A polishing machine comprising opposed abrasion wheels, a rockably mounted 120 standard, shafts supporting the wheels, one of said shafts being journaled in the standard, variably tensioned means for urging the standard in a direction to bring the abrasion wheels together, and a lever controlled means for moving the standard 125 against said tension means.

5. A polishing machine comprising opposed abrasion wheels, means supporting the wheels for relative axial adjustments, 130

- means for supporting work between the wheels for adjustment transverse to the adjustment of the wheels, and means for effecting the individual adjustments.
- 5 6. A polishing machine comprising opposed abrasion wheels, means supporting the wheels for relative axial adjustments, means for supporting work between the wheels for adjustment transverse to the adjustment of the wheels, treadle-controlled means for moving one wheel from the other in a radial direction, and treadle-controlled means for effecting adjustment of said work supporting means.
- 10 7. A polishing machine comprising opposed abrasion wheels, means for supporting the work between the wheels for adjustment transverse to the adjustment of the wheels, treadle-controlled means for moving one wheel from the other in a radial direction, a foot treadle mechanism connected to the work supporting means to adjust the same from one position to another, and stop means for determining the position of such adjustments.

25 In testimony whereof I affix my signature.

CARL H. HEMMING.
